LUBRICATION

John V. Tercho, Turtle Creek, Pa., assignor to
Westinghouse Electric Corporation, East Pitts-
burgh, Pa., a corporation of Pennsylvania

Application April 3, 1945, Serial No. 586,289

8 Claims. (Cl. 184—6)

1

My invention relates to flood-lubricating means for an electric motor or other lubricated device, and it has particular relation to a lubricating means in which a shaft-driven pump, mounted at one end of the motor, supplies oil under pressure to the bearings at both ends of the motor.

Heretofore, the difference in the lengths of the oil-pipe lines from the pump to the bearings at the two ends of the machine has not only resulted in different oil-pressures at the two bearings, because of the difference in the pressure-drops in the respective oil-pipe lines, but it has also resulted in a considerable number of special pipe-connections.

The object of my present invention is to provide an oil-tank which is centrally disposed alongside of the motor or other lubricated device, said oil-tank having both an oil-reservoir and a pressure-oil chamber for receiving the oil, under pressure, which is delivered by the pump from one end of the machine. From this centrally located pressure-oil chamber, oil is delivered to the flood-lubricated bearings at the two ends of the machine, and the overflow-oil is returned from both bearings to the oil-reservoir part of the tank. In this way, I not only equalize the pressure of the oil which is supplied to the two bearings, but I also avoid all of the special pipe-connections which have heretofore been required for the oil-piping.

With the foregoing and other objects in view, my invention consists in the combinations, apparatus, parts, and methods hereinafter described and claimed, and illustrated in the drawing, wherein:

Figure 1 is an end view of the pump-end of a motor embodying my invention.

Fig. 2 is a side elevational view thereof, with parts broken away to show the tank-construction, and

Fig. 3 is a longitudinal sectional view of the bearing.

I have illustrated my invention in a preferred application thereof, in connection with a 200 horse-power, horizontal-shaft, electric motor which is intended for use on shipboard, where the rolling of the ship presents bearing-lubricating problems, by reason of the tilting of the shaft, usually resulting in the requirement of flood-lubrication. The motor is shown at 4. It has an approximately horizontal rotating shaft 5 which is supported by means of two bearings 6, one at each end of the machine. At one end of the machine, there is disposed a shaft-driven pump 7 for pumping oil for the bearings.

2

In accordance with my invention, an oil-tank 8 is centrally disposed alongside of the motor, and this oil-tank has a horizontal partition 9 which divides the tank into an upper oil-reservoir 11 and a lower pressure-oil chamber 12, in the illustrated form of my invention. An oil-line 13 extends to the pump 7 from the oil-reservoir 11, while a second oil-line 14 extends from the pump 7 to the pressure-oil chamber 12. Some sort of pressure-relieving oil-passageway is provided, for discharging some of the oil pumped by the pump 7, so as to maintain a predetermined oil-pressure (assuming a constant-speed motor), depending upon the size of the pressure-relieving passageway. In the particular form of invention which I have illustrated, the pressure-relieving oil-passageway is provided by means of a hole 15 in the partition 9, and preferably this hole is protected by a spaced baffle 16, or other means for horizontally directing the oil which is discharged through said hole 15, so as to prevent the oil from spouting up and splashing against the oil-tank cover 17 and producing foam and oil-mist which would result in oil-leakage. The baffle 17 causes the oil-stream to be broken up in the bottom of the oil-reservoir 11, thus preventing foam.

From the respective ends of the pressure-oil chamber 12, two oil-lines 18 run to the respective bearings 6, where they discharge oil, under pressure, to the tops of the bearings. An oil-drain line 19 extends from each of the bearing-housings to the oil-reservoir 11.

While my invention is applicable to any flood-lubricated bearing, it has been illustrated in connection with a combination oil-ring bearing and flood-lubrication bearing which constitutes the subject-matter of my application Serial No. 586,290, filed concurrently herewith. As shown more in detail in Fig. 3 of the accompanying drawing, this bearing comprises a sleeve-bearing 21 for journaling the shaft. Each bearing has a housing 24 having an oil-chamber 25 in its lower portion. Each bearing also has an oil-ring 26 for lifting oil from the oil-chamber 25 to the top of the journal. The top of the bearing-housing 24 is provided with a slot 27 through which the oil-ring 26 may be inserted or removed, and the slot is closed by a slot-cover 28, which has a downwardly depending oil-pipe 31, extending into close juxtaposition to the top of the oil-ring 26, so as to serve as a keeper for preventing the oil-ring from jumping out of place. The oil-line 18, which supplies oil, under pressure, to the bearing is coupled to the top of the slot-cover 28 for

3 feeding oil through said oil-pipe 31 and pouring it continuously over the bearing, whenever the motor is in normal use.

In the illustrated form of my invention, oil is drained, from the oil-chamber 25, through the oil-drain line 19, in any manner which will maintain a substantially constant oil-level in the oil-chamber 25 of the bearing. This maintenance of a constant oil-level in the oil-chamber 25 is necessary because of the dual function of the illustrated bearing in operating both as a ring-lubricated bearing and as a flood-lubricated bearing. Thus, even though the flood-lubricating means should fail, the oil-ring lubrication is available to bring at least some oil up from the oil-chamber 25 to the top of the journal. If it were not for the presence of the oil-ring 26, or other equivalent means for supplying oil from the oil-chamber 25 to the bearing-portion of the shaft, it would not be necessary to maintain a substantially constant oil-level in the oil-chamber 25.

My present invention relates to the flood-lubricating part of the apparatus, and particularly to the general assembly, including the centrally located tank 8. In operation, oil is pumped from the upper chamber or oil-reservoir 11 of the tank, by means of the pump 1, from which the oil, under pressure, is supplied to the pressure-oil chamber 12 of the tank 8. From this centrally located pressure-chamber 12, oil is supplied to the bearings 6 at both ends of the motor 4, the symmetry assuring the maintenance of substantially identical oil-pressure in the oil-lines 18 to both bearings. In this way, I simplify the oil-piping and the necessary pipe-connections, thus resulting in a considerable saving in cost, while producing a better performance.

It will be obvious that my invention is susceptible of embodiment in several different specific forms, and I desire that the appended claims shall be accorded the broadest construction consistent with their language.

I claim as my invention:

1. A flood-lubricating means for a lubricated device having an approximately horizontal rotating shaft, a bearing for supporting the shaft at each end of the lubricated device, and a shaft-driven oil-pump at one end of the device, said flood-lubricating means comprising an oil-tank centrally disposed alongside of said lubricated device, said oil-tank having a partition dividing the same into an oil-reservoir and a pressure-oil chamber, an oil-line to the pump from the oil-reservoir, an oil-line from the pump to the pressure-oil chamber, the device including means providing a pressure-relieving oil-passageway for discharging some of the oil pumped by said pump, two oil-lines of approximately identical oil-pressure characteristics from the pressure-oil chamber to the respective bearings for flood-lubricating the same, and an oil-line from each bearing to the oil-reservoir for draining oil from each bearing.

2. The invention as defined in claim 1, characterized by said oil-reservoir being above said pressure-oil chamber.

3. The invention as defined in claim 1, characterized by said oil-reservoir being above said pressure-oil chamber, the oil-tank partition being thus horizontal, and said pressure-relieving oil-passageway being provided by a hole in the horizontal partition in the oil-tank.

10 4. The invention as defined by claim 1, characterized by said oil-reservoir being above said pressure-oil chamber, the oil-tank partition being thus horizontal, and said pressure-relieving oil-passageway being provided by a hole in the horizontal partition in the oil-tank, in combination with means for horizontally directing the oil-discharged through said hole in the partition.

15 5. A flood-lubricated device having an approximately horizontal rotating shaft, a bearing for supporting the shaft at each end of the lubricated device, a shaft-driven oil-pump at one end of the device, an oil-tank centrally disposed alongside of said lubricated device, said oil-tank having a partition dividing the same into an oil-reservoir and a pressure-oil chamber, an oil-line to the pump from the oil-reservoir, an oil-line from the pump to the pressure-oil chamber, the device including means providing a pressure-relieving oil-passageway for discharging some of the oil pumped by said pump, two oil-lines from the pressure-oil chamber to the respective bearings for flood-lubricating the same, and an oil-line from each bearing to the oil-reservoir for draining oil from each bearing.

20 30 6. The invention as defined in claim 5, characterized by said oil-reservoir being above said pressure-oil chamber.

7. The invention as defined in claim 5, characterized by said oil-reservoir being above said pressure-oil chamber, the oil-tank partition being thus horizontal, and said pressure-relieving oil-passageway being provided by a hole in the horizontal partition in the oil-tank.

25 45 50 8. The invention as defined in claim 5, characterized by said oil-reservoir being above said pressure-oil chamber, the oil-tank partition being thus horizontal, and said pressure-relieving oil-passageway being provided by a hole in the horizontal partition in the oil-tank, in combination with means for horizontally directing the oil discharged through said hole in the partition.
